DUPLICATING MACHINE

Edmund L. Wall, Detroit, Mich., assignor to Rudolph W. Glasner, Chicago, Ill.

Application April 12, 1934, Serial No. 720,195

10 Claims. (Cl. 90—13.5)

This invention relates to improvements in duplicating machines of the type disclosed in my co-pending application Serial Number 518,528, filed February 26, 1931, and is particularly adapted, though not necessarily limited in its application, to a horizontal type of boring and milling machine.

More particularly this invention relates to that type of machine in which the cutter is controlled by a tracer adapted to follow the profiles of a relatively soft pattern, and although operating against such a soft pattern is designed to control relatively heavy pressure and, in turn relatively heavy cutting machinery.

Still more specifically, the invention relates to a type of machine of this character in which the cutting tool is advanced toward and away from the work by fluid pressure, and which pressure is controlled by the tracer through the medium of an auxiliary valve, the valve operating automatically to direct the fluid pressure to one side or the other of a piston which is operatively connected with the cutting tool, with the result that the pressure operating upon the cutter will be controlled relatively to the position of the tracer on the pattern.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

Figure 1 is a view partly in side elevation, partly broken away, and partly in section, of a machine of this character constructed in accordance with the principles of this invention.

Figure 2 is a detail sectional view on an enlarged scale, of the auxiliary valve and control mechanism for the cutter.

Figure 3 is a view similar to Figure 2, of the auxiliary valve, on an enlarged scale, showing a portion of the cylinder in which the pistons that control the movement of the cutter, operate.

Figure 4 is a view similar to Figure 3, showing the auxiliary valve and others of the parts in different positions from that shown in Figure 3.

Figure 5 is a detail sectional view taken on line 5—5, Figure 4.

Figure 6 is a view partly in elevation and partly in section, of the tracer.

This invention is adapted to be applied to any standard drilling or boring machine in which the cutter tool is mounted upon the knee of the ma-

chine and is moved toward and away from the work, as well as in vertical and horizontal directions by any well known means.

The present invention, however, is more particularly concerned in the movement of the cutter 10 over the work 11, and which movement is influenced by the operation of a tracer 12 over the surface of a pattern 13, the latter being constructed preferably of some soft or cheap material, while the work 11 is constructed of some hard material.

In carrying out the invention, the tracer 12 is mounted upon a slide 14 which moves in guides 15—16 while the cutter 10 is mounted upon the slide or carriage 17 movable in suitable guides, such as the guide 16 and the guide 18. These slides or carriages 14—17 may be connected together for simultaneous movement in any suitable manner, such as by means of a connecting bracket or yoke 19 so that when the slide 17 is moved forwardly and backwardly the tracer and the cutter will be correspondingly moved so as to initially position the tracer and the cutter for operation.

The specific construction of the tracer mechanism constitutes a portion of the subject matter of my co-pending application Serial Number 702,039, filed December 12, 1933, but will be described somewhat in detail in order that a complete understanding of the construction and operation of the same in connection with the present invention, may be had.

The tracer 12 is caused to bear at its point upon the surface of the pattern 13 by means of a spring 20 which acts through the medium of interposed elements and abuts a barrel 21 which is adjustable so that the tension of the spring may be varied. It is solely the spring tension that determines the pressure of the tip of the tracer 12 against the pattern 13, and not the pressure fluid which traverses the tracer mechanism and is controlled in its flow by the tracer.

The barrel 21 is screwed into the head 22 which closes one end of the cylinder 23. The other end of this cylinder is closed by a cap 24 which has an enlarged opening providing a clearance for the necessary side motion of the shank of the tracer 12.

A combined piston and balanced valve which is the chief element of a movable valve structure, operates in the cylinder 23 between its closed ends, and the piston elements are designated by the reference characters 25—26. These are integral with the sleeve 27 which carries a circular valve plate 28. This valve plate occupies an

annular chamber 29, and it is against one edge 30 of the chamber 29 that the valve plate 28 sits in order to cut off flow of pressure fluid. The edge 30 therefore constitutes a valve seat, and 5 the cap 24 which is adjustably secured to the end of the cylinder 23 is additionally used for adjusting the valve plate 28 at the seat 30.

An inlet 31 communicates with the chamber 29 and fluid is introduced into the cylinder 23 between the piston elements 25 and 26 since the 10 upright portions of the element 25 and the plate 28, as well as that part of the sleeve 27 disposed therebetween, constitute movable walls of the chamber 29, it follows that a movement of the 15 so-called piston or hollow valve 27 may occur to the right or toward the end 22 of the cylinder 23, without the necessity of the valve plate 28 having to act against fluid pressure.

In other words, when the valve plate 28 is seated, the various walls constituting parts of the element 25, sleeve 27, cylinder 18 and plate 24, will confine a volume of pressure fluid which is readily displaced by a movement of the tracer 12 to the right, the only resistance being the 20 tension of the spring 21. Therefore, when the tracer encounters a raised place in its travel along the pattern 13, the tracer 12 will be displaced with the utmost ease. The pressure of the tracer 12 is regulated by the regulation of the spring 20 and the spring may be adjusted to such a light tension that even the softest pattern ordinarily employed may be traced without 25 injury.

A fluid outlet 32 communicates with the cylinder 23 on the right side of the piston element 25. The base 33, of which a guide stem 34 is a part, is preferably peripherally smaller than the bore of the cylinder 23, so that there may be no obstruction of fluid flowing through openings 35 30 to the outlet 32, and the base 33 is preferably secured to the piston by being screwed thereupon.

A port or opening 36 is provided in the hollow valve 27 to form a passageway for the fluid. When the valve plate 28 is unseated from the seat 30 there will be a flow of fluid from the inlet 31 45 into the chamber 29, past the valve seat 30 and into the cylinder 23, thence through the opening 36 and out of the ports or openings 35 to the outlet 32. A cup 37 is provided with a rim having a sharp seating edge 38 bearing against 50 a disc 39 carried by the tracer 12. A part of this cup has an opening 40 which provides a drain passage to accommodate oil seeping past the sleeve valve 27 at the end 28.

There is a separation between the cup 37 and the disc 39 but the two parts are generally kept in contact by virtue of the engagement of the tracer 12 with the pattern and the pressure of the spring 20 in that direction. The tendency of the 55 spring is to keep the disc 39 pressed against the flange of the cap 24.

Fluid pressure is applied to the tracer 12 from a tank or sump 41 through the medium of a pump 42, the inlet 43 of which receives the fluid 60 from the sump, and to the outlet is connected a flexible tube pipe 44, which in turn is connected to a tube or pipe 45, the latter being connected to the pipe 46, and this pipe 46 in turn is connected to the inlet opening 31 of the cylinder 23, and an overflow 47 is connected to the pump 42, as a safety for excess pressure, a valve 48 being arranged in the outlet.

Connected with the outlet 32 of the cylinder 70 75 23 is a pipe 49, preferably flexible, which in turn

is connected to an exhaust pipe 50, leading back to the sump 41.

Within the pipe 46 and between the connection 45 and the inlet 31 of the cylinder 23 is arranged a regulator valve 51.

The cutter 10 is secured to a spindle 52 which in turn is connected to the boring bar 53 of the machine to which this attachment is applied, and the end of the spindle abuts ball bearings 54, the latter having a bearing against a thrust collar 10 55 secured to the bar 53 in any suitable manner.

The boring bar passes through an annular casing 57, and which casing constitutes an annular cylinder 58 in which a piston preferably comprising the elements 59—60 operates, and between 15 the piston elements is arranged opposed cup shaped packing members 61. Connected to the piston thus formed, are piston rods 62, any number of which may be provided, and these rods are secured thereto at one end and in any suitable 20 manner, and pass through packing glands 63. The forward ends of the rods are secured to a yoke 64, which in turn is secured to the spindle 52 by a suitable fastening device 65, so that when the piston is reciprocated or moved in the cylinder 58, the spindle 52 and consequently the boring 25 or cutting tool 10 will be correspondingly moved.

The movement of the piston is controlled by an auxiliary valve 66, which moves in a valve casing 67. The valve casing is provided with an inlet 68 30 through the side thereof, and ports 69—70 through the opposite side thereof, preferably in proximity to the inlet 68, and these ports 69—70 constitute both inlet and outlet ports for the fluid, the ports 69—70 being preferably separated by 35 means of the wall 71.

The port 69 leads to the front end of the cylinder 58 by means of a passage 72, and a port or opening 73, while the port or passage 70 has communication with a passage 74 which leads to the 40 other end of the cylinder 58 on the opposite side of the piston through the medium of a port 75, so that when the fluid is directed from a pipe 76 which communicates with the inlet 68 of the casing 67 and which has communication with the 45 pipe 45, and when the valve 66 which operates in the casing 67 is positioned to direct the fluid through the passage 72 to one side of the piston in the cylinder 58, the tool 10 will be retracted and the fluid on the opposite side of the piston 50 will be exhausted through the passage 74, in a manner to be described, allowing the piston to move towards the other end of the cylinder 58. When, however, the valve 66 is in a position to cause the fluid entering the casing 67 through the 55 pipe 76 to be discharged into the passage 74 on the other side of the piston, the piston and the cutter 10 will be moved in the opposite direction, and the fluid in advance of the piston will be exhausted through the opening 73, passage 72 and 60 port or passage 69, in a manner to be described.

It will therefore be manifest that by control of the valve 66, the direction of movement of the cutter lengthwise of its axis will be controlled.

The inlet 68 of the casing 67 has communication with an annular chamber 77, and on each side of the annular chamber 77 and spaced therefrom are annular ports or passages 78—79 which in turn have communication with a passage 80 opening through the casing, and to which opening is connected an exhaust pipe 81 that leads back to the sump 41 either directly or by being connected with the exhaust pipe 50, as at 82 (see Figure 1).

The casing 67 is also provided with annular 75

passages 83—84. The passage 83 has communication with a port 85 communicating with the port or passage 70, and the passage 84 has communication with a port or passage 86 which in 5 turn has communication with the port or passage 69.

The valve 66 is provided with peripheral channels 87—88—89 to form walls 90—91, and the 10 passages 87 and 89 are of a length to form communications respectively between the passages 78 and 83, 84 and 79, while the passage 88 is of such a length as to form communication either between the passage 77 and passage 83 or the 15 passage 77 and passage 84, according to the direction of movement or position of the valve 66.

The walls 90 and 91 of the valve 66 respectively 20 co-operate with seats 92—93 and 94—95.

When the valve 66 is in the position shown in Figure 2, the passage 77 will have communication 25 with the passage 88 but as communication between the passage 88 and the passages 83—84 is closed, the fluid will be confined within the annular passage 77 and cannot escape. The valve 66 is normally held in a neutral position or in the 30 position shown in Figures 2 and 4, by means of a spring 96 which encompasses a stem 97 that is secured to the valve and which passes through a bearing 98. One end of the spring 96 abuts the bearing 98 and the other end abuts the end of 35 the valve 66 and tends normally to move the valve 66 forwardly. A spring 99 also encompasses the stem 97 on the other side of the bearing 98 and abuts the bearing at one end and has engagement at the other end with a collar 100 on the 40 stem. This spring 99 is preferably of a tension less than the tension of the spring 96 and serves the purpose of initially moving the valve 66 from the position shown in Figures 2 and 3, to the position shown in Figure 4, at certain times in the 45 operation of the machine. At the time when there is a complete exhaustion of the fluid from the casing 67 in advance of the valve 66 there would be a tendency for suction to draw the valve 66 forwardly, which is not desirable and therefore the spring 99 is provided which overcomes such 50 tendency and relieves the load thereon.

Bumpers or cushions 101—102 may be provided which act as shock absorbers to the movement of the valve 66 and these cushioning elements are 55 mounted upon a rod or bar 103 secured to the valve 66 and which pass through the bearing 98, the bumpers 101—102 being arranged on opposite sides of the bearing.

Connected with the pipe 46 (see particularly 60 Figure 1) at a point preferably between the valve 51 and the inlet 31 of the casing 23 of the tracer, as at 104, is a pipe 105, which has communication with an inlet opening 106 in the valve casing 67. This opening 106 communicates with a 65 chamber 107 in the valve casing 67 in advance of the valve, a packing gland or washer 108 being preferably provided on the end of the valve 66, which abuts an annular flange 109 on the valve, and it is the suction which has a tendency 70 to be created in the chamber 107 to move the valve 66 forwardly that the spring 99 is provided to overcome.

When the tracer 12 is in its extreme forward 75 position and both the tracer 12 and the cutter 10 are out of contact respectively with the pattern and the work, there will be exerted the greatest pressure from the pump 42 through the pipe 45, pipe 16 and back of the piston in the cylinder 58, moving the cutter forward to its extreme forward position, and the cutter will be held in such

position under the greatest pressure because at that time the auxiliary control valve 66 will be in the position shown in Figure 4, and the tracer will be in its extreme position forwardly as shown in Figure 6.

The fluid under pressure will then flow from the pump 42, through the pipe 45, past the valve 51, through the pipe 46, into the opening 33 in the casing 23 of the tracer and into the chamber 29, where it will be confined, owing to the fact 10 that the valve plate 28 is seated upon the seat 30 to prevent the escape of the fluid from the tracer casing 23. At the same time a part of the fluid under pressure will flow from the pipe 45 into the pipe 76 into the annular chamber 77 of the valve 15 casing 67 (see Figure 4), through the port 92, into the passage 83, through the port 85, into the port 70 20 76, thence into the passage 74, through the opening 75 and behind the piston 59—60 in the cylinder 58 to move the latter to the position shown in Figure 4.

When the tracer contacts with the pattern 13 it will be forced backwardly, the distance of the movement of the tracer being controlled by the profile of the pattern. As the tracer 12 is forced backward (see Figure 6), the valve 27 will be moved backwardly against the stress of the spring 20 so as to move the valve plate 28 off of the seat 30, thereby establishing communication between the chamber 29 in the tracer casing and the port or opening 36 in the valve 27. The fluid will then flow through the opening 36, out of the openings 35, thence through the exhaust pipe 49—50, back to the sump 41. Before the tracer 12 is moved backwardly, shifting the valve 27 to permit the fluid pressure from the chamber 29 to be exhausted, the auxiliary valve 66 will be held in the position shown in Figure 4 and against the stress of the spring 96 by reason of the fact that pressure from the pump 42 will be manifested upon the end of the valve 66, through the pipe 105. When, however, the pressure in the chamber 29 of the tracer casing 23 is relieved by the movement backwardly of the tracer 12 so as to permit the fluid to flow out of the exhaust pipe 50, the pressure in the auxiliary valve chamber 67 in advance of the valve 66 will be relieved through the pipe 105 and the valve 66 will be moved forwardly from the position shown in Figure 4 to the position shown in Figure 2, by the spring 96, thereby establishing communication between the ports and passages 69—72 and 73 leading to the other side of the piston 59—60 and the pipe 76 so that fluid under pressure will flow from the 55 pipe 76 into the annular chamber 77 which now has communication with the port or passage 69, through the port 86, and the fluid pressure will then be directed through the passage 72 and port 73 on the other side of the piston 59—60 moving the latter backwardly and with it the cutter 10. At the same time that communication is established between the annular chamber 77 and the valve casing 67 and the port or passage 86, communication will also be established between the 60 65 passages 74—70, port 85, passage 78, and exhaust passage 80 with which the exhaust pipe 81 communicates.

Similarly, when the fluid pressure is directed 70 behind the piston 59—60 to move it forwardly, the fluid in advance of the piston will be exhausted through the passage 73 (see Figure 4), passage 72, port 69, port 86, passage 79, which communicates with the exhaust passage 80, and which latter communicates with the exhaust pipe 81. 75

Thus it will be seen that by a manipulation or actuation of the tracer 12 over the profile of the pattern 13, the position of the auxiliary valve 66 will be controlled, and in accordance with the position of this valve 66, the movement of the piston 59—60 will be controlled, and this in turn will move the cutter toward or away from the work 11, that is to say the tracer acts to position or shift the auxiliary valve 66 to control the flow 10 of fluid or pressure in advance of or behind the piston 59—60.

The valve 51 is provided as a pressure control valve by means of which the fluid pressure may be varied.

15 The cutter 10 is rotated in any desired or suitable manner, such as by means of a gear 110 which is secured to a shaft 111 that is rotated from any suitable source of power. The gear 110 is preferably of the bevel type and meshes with a gear 20 112 which is keyed or splined upon the bar or shaft 53, the gear 112 being fixed so that when the cutter 10 is advanced or retracted, the shaft 53 will slide through the gear 112.

25 While the preferred form of the invention has been herein shown and described, it is to be understood that various changes may be made in the details of construction and in the combination and arrangement of the several parts, within the 30 scope of the claims, without departing from the spirit of this invention.

What is claimed as new is:—

35 1. In a duplicating machine, a work cutter, a piston connected with the cutter, a cylinder in which the piston moves, ports leading into the cylinder on opposite sides of the piston, each operating as a fluid inlet and outlet, an auxiliary valve casing constituting with said cylinder a unitary structure, said auxiliary valve casing having ports communicating with the first 40 said ports, a fluid pressure supply opening to the valve casing, a fluid exhaust from the valve casing, a valve in said casing, mechanical means tending normally to move said valve in a direction to establish communication between said 45 fluid opening and one end of said cylinder and also to establish communication between said exhaust and the other end of the cylinder for moving the cutter toward the work, a pattern tracer which is subject to vibrations by the intricacies of a pattern, means to supply the fluid 50 pressure to said tracer and to one side of the said valve to move the latter against the stress of the first said means to cause said valve to establish communication between the said fluid opening and the other end of the cylinder on the opposite 55 side of the piston, and means whereby the vibration of the tracer will control the operation of said valve.

60 2. In a duplicating machine, a work cutter, fluid pressure means for moving the cutter towards and away from the work, means embodying a reciprocable valve for causing the respective movements of the cutter, mechanical means 65 tending normally to move the valve in one direction, means for directing fluid pressure against the valve to move it in the opposite direction against the stress of the last said means, a vibratable tracer movable over a pattern for 70 controlling the operation of the cutter, means responsive to the vibration of said tracer and operating to cause the fluid pressure against the said valve to be increased to move the latter in one direction and to cause such fluid pressure to be 75 reduced to permit the valve to be moved in the

opposite direction, means for creating such fluid pressure, means for varying at will the said fluid pressure, and means for overcoming suction exerted upon the valve which would have a tendency to prevent operation of the valve when relieved of the actuating fluid pressure thereupon. 5

3. In a duplicating machine, a work cutter, fluid pressure means operating to move the cutter in directions both towards and away from the work, a valve for controlling the direction of movement of said cutter under the action of said fluid pressure, a pattern tracer subject to vibratory action as it moves over a pattern, mechanical means for moving said valve in one direction, fluid pressure means for moving the valve in the opposite direction against the stress of the last said means, means whereby the vibratory action of said tracer will control the said fluid pressure, to cause the valve to be moved thereby against the stress of second recited means, and to reduce the fluid pressure against said valve to permit the valve to be moved by the second recited means, means for cushioning the movement of the valve, said cushioning means embodying a member carried by and extending from the valve, a bearing through which said member slides, and bumpers carried by the member on opposite sides of the bearing. 15 20 25

4. In a duplicating machine, a work cutter, fluid pressure means operating to move the cutter in directions both towards and away from the work, a valve for controlling the direction of movement of said cutter under the action of said fluid pressure, a pattern tracer subject to vibratory action as it moves over a pattern, means for moving said valve in one direction, fluid pressure means for moving the valve in the opposite direction against the stress of the last said means, means whereby the vibratory action of said tracer will control the said fluid pressure, to cause the valve to be moved thereby against the stress of second recited means and to reduce the fluid pressure against said valve to permit the valve to be moved by the second recited means, and additional mechanical means operating upon said valve in opposition to the second recited means for imparting an initial movement to the valve against the stress of the first said means at a predetermined time in the 40 45 50 operation of the machine.

5. In a duplicating machine, a work cutter, a piston connected with the cutter, a cylinder in which the piston operates, a fluid pressure line, a pattern tracer subject to vibratory action as it moves over a pattern, means whereby the vibrations of the tracer will cause the fluid pressure from said line to be alternately directed to opposite sides of the piston and correspondingly relieved from the other side thereof, whereby the cutter will be moved by such pressure towards and away from the work, the said means embodying a valve in the pressure line, means tending normally to move the valve in one direction against such pressure, said fluid pressure being operable 65 to move the valve in the opposite direction, means influenced by said tracer to reduce the pressure of the fluid against the valve to permit the valve to be moved by the last said means, and additional mechanical means for initially moving the valve, 70 against the stress of the second recited means when the fluid pressure against said valve is temporarily reduced to a predetermined point in the cycle of operation of the machine.

6. In a duplicating machine, a work cutter, a 75

piston connected with the cutter, a cylinder in which the piston operates, a fluid pressure line, a pattern tracer subject to vibratory action as it moves over a pattern, means whereby the vibrations of the tracer will cause the fluid pressure to be alternately directed to opposite sides of the piston and correspondingly relieved from the other side thereof, whereby the cutter will be reciprocated towards and away from the work, 5 the said means embodying a reciprocable valve in the pressure line, resilient means tending normally to move the valve in one direction, said fluid pressure operable to move the valve in the opposite direction against the stress of said resilient means, means influenced by the tracer to reduce fluid pressure against said valve to permit the valve to be moved by said resilient means, and additional resilient means operable upon said valve to initially move the valve against the stress 10 of the first recited resilient means at a predetermined time in the cycle of operation of the tracer.

7. In a duplicating machine, a work cutter, a piston connected with the cutter, a cylinder in which the piston operates, a fluid pressure line, a pattern tracer subject to vibratory action as it moves over a pattern, means whereby the vibrations of the tracer will cause the fluid pressure to be alternately directed to opposite sides of the piston and correspondingly relieved from the other side thereof, whereby the cutter will be reciprocated towards and away from the work, the said means embodying a reciprocable valve in the pressure line, resilient means tending normally to move the valve in one direction, said fluid pressure operable to move the valve in the opposite direction against the stress of said resilient means, means influenced by the tracer to reduce fluid pressure against said valve to permit the valve to be moved by said resilient means, additional resilient means operable upon said valve to initially move the valve against the stress of the first recited resilient means at a predetermined time in the cycle of operation of the tracer, 20 and cushioning means for limiting the movements of the said valve.

8. In a duplicating machine, a work cutter, a piston connected with the cutter, a cylinder in which the piston operates, a fluid pressure line, 25 connections between said line and the cylinder on opposite sides of the piston to reciprocate the latter, a valve in the line for controlling the direction of flow of the fluid with respect to the cylinder, resilient means for moving the valve in one direction, means whereby the fluid pressure will

act upon the valve to move it in the opposite direction, a tracer vibratable by movement over a pattern, means responsive to the movements of the tracer to cause fluid pressure to be relieved from said valve to permit the valve to be moved by the said resilient means, and additional mechanical means operable upon said valve for initially moving the valve against the stress of the said resilient means to overcome suction on the valve created by the relieving of the fluid pressure on the valve. 10

9. In a duplicating machine, a work cutter movable in directions towards and away from the work, a pattern tracer subject to vibratory action as it moves over a pattern, a pressure fluid system 15 including a cylinder and piston for utilizing the pressure to move the cutter in directions towards and away from the work, means controlled by the vibrations of the tracer to variably control the flow of fluid to the cylinder and to control the direction of flow of fluid into the cylinder to cause the active pressure of the fluid to be transferred from one side to the other side of the piston, the said means embodying a distributing valve, means tending normally to move the valve 20 in one direction, the said valve being operated upon by said fluid pressure to move the same in the opposite direction against the stress of the last said means, and means in addition to said fluid pressure for moving the valve against the 25 stress of the last recited means.

10. In a duplicating machine, a work cutter, a piston connected with the cutter, a cylinder in which the piston operates, a fluid pressure line, a pattern tracer subject to vibratory action as 30 it moves over a pattern, means whereby the vibrations of the tracer will cause the fluid pressure to be alternately directed to opposite sides of the piston and correspondingly relieved from the other side thereof, whereby the cutter will be reciprocated toward and away from the work, the 35 said means embodying a reciprocable valve in the pressure line, resilient means tending normally to move the valve in one direction, said fluid pressure operable to move the valve in the opposite 40 direction against the stress of said resilient means, means influenced by the tracer to reduce fluid pressure against said valve to permit the valve to be moved by said resilient means, and additional mechanical means operable upon said 45 valve to initially move the valve against the stress of the said resilient means at a predetermined time in the cycle of operation of the tracer. 50

EDMUND L. WALL. 55
